DESIGN FOR WALL-PAPER.

SPECIFICATION forming part of Design No. 22,906, dated November 14, 1893.

Application filed October 9, 1893. Serial No. 487,672. Term of patent 8½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of vertical stripes formed of wavy lines of ribbon with interlacing vines of leaves, and between the stripes are disposed at regular distances apart a series of ornaments having a fleur-de-lis shaped base with a vase-shaped top filled with flowers and leaves as represented in the accompanying drawing. The border or upper portion of the design is formed of interlacing ribbons connecting similarly shaped ornaments and sprays of flowers and leaves ar-

ranged centrally between two of said ornaments as represented in the accompanying drawing. An ornamental band composed of light parallel lines inclosing small ornamental form a dividing line between the hanging and the border as shown.

What I claim is—

1. The design for wall paper herein shown and described.
2. In the design for wall paper, the border herein shown and described.

Witness my hand this 5th day of October, 1893.

CHARLES BOOZE.
